UNITED STATES PATENT OFFICE.

PAUL RIEGGER, OF BADEN, GERMANY, ASSIGNOR TO KIENZLE UHRENFABRIKEN AKTIENGESELLSCHAFT, OF SCHWENNINGEN-ON-THE-MAIN, GERMANY, A CORPORATION OF GERMANY.

FARE INDICATOR.

Application filed November 11, 1924. Serial No. 749,205.

My invention relates to improvements in fare indicators.

Fare indicators such as are now in use are provided with three digit members or 5 numeral wheels, the first one representing the tens of the smaller denomination of the money, such for example as the cents, while the other digit carriers represent the units and tens of the larger money denomination, 10 such for example as the dollars. If by each operation of the indicator each step in the addition is in ten units of the smaller money denomination (cents) then a stationary zero indication may be used and only the units 15 of the tens advanced by the indicator operation.

Fare indicators of this type are satisfactory in case of currencies of median value. But in case of currencies of low value it is 20 frequently necessary to indicate amounts having more than 99 units of the large denomination so that the standard fare indicator is insufficient. On the other hand in case of currencies of higher value, such for 25 example as the dollar currency, it is desirable to advance the smaller units, not by ten but by smaller numbers, such as five.

The object of the improvements is to provide a simple construction adapted to be 30 mounted in standard fare indicators for increasing the number of the figures, so that the fare indicators are capable of registering larger numbers in case of currencies of low value and of registering units of the small 35 denomination in case of currencies of high value. With this object in view my invention consists in providing a fourth digit carrier behind the third one and connecting the same by a suitable mechanism to the third 40 carrier for being shifted in a similar way as the second and third digit carriers.

In the preferred form of the invention I do not use a mechanism comprising interlocking gears for driving the fourth digit 45 carrier, but I use mechanism requiring less power and comprising a cam operated by the mechanism of the third digit carrier and adapted to rock a spring pressed member carrying a pawl engaging in a ratchet wheel connected with the fourth digit carrier.

Another object of the improvements is to provide an improved setting member or

wing lever for setting the fare indicator in the desired operative or inoperative positions, and with this object in view I connect 55 the wing member or handle with its shaft by casting the wing member to the end of the shaft. Thereby a reliable joint between the shaft and the wing member is obtained, and the wing member is strong in construction. 60

For the purpose of explaining the invention an example embodying the same has been shown in the accompanying drawing in which the same reference characters have been used in all the views to indicate corresponding parts. In said drawing,

Fig. 1, is an elevation of the fare indicator with the front plate removed to show the parts of the mechanism to which my invention relates,

Fig. 2, is an elevation showing the end of the shaft of the setting member or wing lever and the wing carried thereby, the wing or handle being shown in broken lines, and

Fig. 3, is a plan view of Fig. 2.

In the example shown in Fig. 1 the fare indicator comprises a driving shaft 3 mounted in bearings 1 and 2 and adapted to be operated from a wheel of the carriage or a clock work, as is known in the art. A worm 40 provided on the shaft 3 is in engagement with a worm gear 5 secured to a shaft 6 carrying a ratchet wheel 7. The teeth 8 of the ratchet wheel 7 are engaged by an arm 10 of a bell crank lever having a rocking support at 11 and acted upon by a spring 9 tending to hold the same in engagement with the said teeth. The other arm 12 of the said bell crank lever carries a pawl 13 pressed by a spring 14 into engagement with the teeth 90 of a ratchet wheel 15 mounted on a shaft 16 carrying a gear wheel 17. The gear wheel 17 is in mesh with a gear wheel 18 mounted on a shaft 19 and carrying the first digit disk 20.

Further, the shaft 19 carries a disk 21 provided with a tooth 22 adapted for engagement with pairs of teeth 23 projecting from the circumference of a disk 24. The disk 24 carries ten pairs of teeth 23, and it is secured to the shaft 25 of the second digit disk 26. To the shaft 25 a second disk 27 is secured which carries at its circumference a tooth 28. The latter is adapted for cooperation

with pairs of teeth 29 projecting beyond the circumference of a disk 30. The disk 30 is secured to a shaft 31 of the third digit disk 32, the disk 30 likewise carrying ten pairs of teeth 29.

To the shaft 31 a cam disk 33 is secured which is engaged by a pin 34 of a lever 36 having a rocking support at 35. On a pin 37 of the said lever a pawl 38 and a plate 39 are 10 rockingly mounted. The pawl 38 is acted upon by a spring (not shown) tending to hold the same in engagement with the teeth of a ratchet wheel 40 mounted on a shaft 41 of a fourth digit carrier 42. A spring 43 15 tends to hold the arm 36 in the position shown in Fig. 1 in which the pin 34 is pressed on the circumferential face of the cam 33.

The plate 39 carries pins 44 and 45, the 20 pin 45 having a link 46 jointed thereto. The said link is jointed with its opposite end to an arm 47 of a lever rockingly mounted on a pivot bolt 48 provided on the lever 36. The other arm 49 of the said lever is in position 25 for engagement by a pin 50 secured to an arm 51 of a bell crank lever 51, 53 the arm 53 of which carries a roller 54 adapted to be engaged by an arm 57 secured to a setting shaft 55 carrying the setting or wing lever 30 56, a spring 58 tending to hold the bell crank lever 51, 53 in the position shown in Fig. 1. The lever 47, 49 is acted upon by the spring 43 passed around a pin 59 secured to the arm 49 and tending to hold the lever 47, 49 in 35 the position shown in the figure. A shoulder 60 provided on the lever 47, 49 is adapted for engagement with a pin 61 secured to the lever 36. On a pivot bolt 62 a pawl 63 is mounted which is pressed by a spring 64 40 into engagement with the teeth of the ratchet wheel 40. Further the said teeth are engaged by a pin 65 secured to the lever 36 and provided for preventing overthrowing of the ratchet wheel 40.

45 In the operation of the apparatus the rotary movement of the shaft 3 is transmitted through the parts 4, 5, 7, 8, 10, 12, 13 and 15 to the shaft 16 and from the latter through the gear wheels 17, 18 to the shaft 19. The movement of the shaft 19 is transmitted by the tooth 22 and the pairs of teeth 23 to the shaft 29 and from the latter through the tooth 28 and the pairs of teeth 29 to the shaft 31.

55 From the shaft 31 the fourth digit carrier 42 is moved as follows:

60 As the shaft 31 rotates the pin 34 is pressed outwardly by the cam 33. Thereby the lever 36 and the pawl 38 are rocked to the left, and the pawl 38 is pressed by a spring (not shown) into position at the rear of the next tooth of the ratchet wheel 40. After complete rotation of the cam 33 the pin 34 is released from the cam face so that 65 it can be returned into the position shown in

Fig. 1. Therefore, the lever 36 is retracted by the spring 43 the pawl 38 advancing the ratchet wheel 40, the shaft 41 and the disk 42 mounted thereon one step.

The first disks 20, 26, and 32 are connected 70 in the usual way by interlocking gears 22, 23, 28, 29, while the third and fourth disks 32 and 42 are connected by a cam disk 33 and the parts operated thereby. A gear of this type requires comparatively little power. 75 When providing a connection comprising interlocking gears between the third and fourth disks the power required for the operation of the indicator would be too large, and it would be necessary to provide heavier 80 gears in order to insure correct operation of the disk 42. This, however, would be objectionable because it would be difficult to mount the fourth disk 42 and associated parts in standard fare indicators provided 85 with three disks.

The three disks 20, 26, 32 are provided with resetting means of ordinary construction and I deem it not necessary to describe the said means, the resetting mechanisms being operated when moving the wing lever 56 from the 270° position into the zero position, so that the arm 57 acts on the roller 54 and lifts the arm 53. Thereby the arm 51 and the arm 49 are rocked downwardly. Thereby 95 the link 46 rocks the plate 39 about the pin 37, so that the pin 44 retracts the pawl 38 away from the teeth of the ratchet wheel 40. Thereafter, the shoulder 60 engages the pin 61 of the arm 36 which is therefore rocked 100 to the left thus retracting the pin 65 away from the teeth of the ratchet wheel 40. Further, a pin 66 secured to the arm 49 acts on the free end of the pawl 63 and lifts the same out of engagement with the teeth of the 105 ratchet wheel 40. Now the shaft 41 is free to rotate the disk 42, which is done by means of a resetting spring (not shown) for resetting the same.

When the wing lever 50 is in the 90°-position the parts of the mechanism are in the 110 positions shown in Fig. 1.

As appears from Fig. 2 the wing or handle 56 is connected with the shaft 55 by casting. In order to insure a reliable joint between 115 the shaft 55 and the wing 56 when casting the parts together, the shaft 55 is provided at one end with an angular groove 67 and two plane faces 68, 69 preventing displacement of the wing 56 on the shaft 55 when the joint should be loosened. I have found that thereby a reliable joint between the shaft 55 and the wing 56 is insured.

120 Preferably, tables 71 carrying the inscription "Free" are secured to one or both sides of the plate 70 of the wing 56, which plates are secured in position by means of thin short tubular rivets 72 of copper passed through corresponding bores of the tables 71 and the plate 70 and upset at their ends. 125

To insure correct position of the tables 74 of the plate 70 I prefer to provide the plate 70 with projecting rims 73 running all around the tables 71. Thus the tables 71 do not project beyond the margin of the plate 70.

5 To prevent rattling of the tables when loosened on the rivets a spring 75 is disposed in a hole 74 of the plate 70, which 10 spring acts on the inner faces of the tables and tends to push the same outwardly.

I claim:

1. In a fare indicator, the combination, with a plurality of digit carriers of lower order connected by interlocking gears of a digit carrier of higher order, a cam rotatable with a carrier of lower order, and mechanism operated by said cam for moving the carrier of higher order.
- 15 2. In a fare indicator, the combination, with a plurality of digit carriers of lower order connected by interlocking gears, of a digit carrier of higher order, a cam rotatable

with a carrier of lower order, and pawl and ratchet mechanism operated by said cam for 25 moving the carrier of higher order.

3. In a fare indicator, the combination, with a plurality of digit carriers of lower order connected by interlocking gears, of a digit carrier of higher order, a cam rotatable 30 with a carrier of lower order, a ratchet wheel connected with the digit carrier of higher order, a lever adapted to be operated by said cam and carrying a feed pawl in engagement with said ratchet wheel for advancing the 35 same, means on said lever adapted for engagement with said ratchet wheel for preventing overthrowing thereof, and a stop pawl engaging said ratchet wheel for preventing return movement thereof when re- 40 tracting said feed pawl on the lever away from said ratchet wheel.

In testimony whereof I hereunto affix my signature.

PAUL RIEGGER.
